(57) **CLAIM**

The ornamental design for a front panel for a packaged terminal air conditioner, as shown and described.

DESCRIPTION

FIG. 1 is a perspective view illustrating the front, right side and top of the front panel of a packaged terminal air conditioner;

FIG. 2 is a front elevational view thereof;

FIG. 3 is a right side view thereof;

FIG. 4 is a left side view thereof;

FIG. 5 is a top plan view thereof; and,

FIG. 6 is a bottom plan view thereof.

FIGS. 2-6 are shown on an enlarged scale.

The broken lines shown in the drawings are environmental only and form no part of the claimed design.
